(57) **CLAIM**

We claim the ornamental design for a display screen with an animated graphical user interface, as shown and described.

DESCRIPTION

FIG. 1 is a front view of a first image in a sequence for a display screen with an animated graphical user interface showing the new design;

FIG. 2 is a second image thereof;

FIG. 3 is a third image thereof;

FIG. 4 is a fourth image thereof; and,

FIG. 5 is a fifth image thereof.

The broken line showing of the outermost rectangle in the drawings and a hand in FIG. 2 depicts environmental subject matter and forms no part of the claimed design. The remaining broken lines illustrate portions of the display screen with an animated graphical user interface that form no part of the claimed design.

The appearance of the transitional image sequentially transitions between the images shown in FIGS. 1-5. The process or period in which one image transitions to another image forms no part of the claimed design.
